(57) **CLAIM**

We claim the ornamental design for a landscape edging, as shown and described.

DESCRIPTION

FIG. 1 is a front view of the landscape edging.

FIG. 2 is a back view.

FIG. 3 is a top view.

FIG. 4 is a cross sectional view taken along line 4—4 of FIG. 1.

FIG. 5 is a cross sectional view taken along line 5—5 of FIG. 1.

FIG. 6 is a bottom view.

FIG. 7 is a front view of a second embodiment of the landscape edging.

FIG. 8 is a back view.

FIG. 9 is a top view.

FIG. 10 is a cross sectional view taken along line 10—10 of FIG. 7.

FIG. 11 is a cross sectional view taken along line 11—11 of FIG. 7; and,

FIG. 12 is a bottom view.

The claimed design is shown fragmented on the ends to indicate indeterminate length.

Portions shown in broken lines are for illustrative purposes only and form no part of the claimed design.
